UNITED STATES PATENT OFFICE.

WILLIAM H. SAUVAGE, OF FLUSHING, NEW YORK, ASSIGNOR, BY DIRECT AND MESNE ASSIGNMENTS, TO THE ATLANTIC HAND BRAKE CORPORATION, OF BUFFALO, NEW YORK, A CORPORATION OF NEW YORK.

RAILWAY HAND-BRAKE.

1,306,635.

Specification of Letters Patent. Patented June 10, 1919.

Application filed March 20, 1918. Serial No. 223,530.

To all whom it may concern:

Be it known that I, WILLIAM H. SAUVAGE, a citizen of the United States, residing at Flushing, in the county of Queens and State 5 of New York, have invented certain new and useful Improvements in Railway Hand-Brakes, of which the following is a specification.

This invention relates to hand brakes particularly applicable for use on freight cars, 10 street cars, and the like.

One of the objects of the present invention is to provide a simple and practical hand brake of the above general character 15 having relatively few parts which will be inexpensive to manufacture and install. A further object is to provide a hand brake of that type known to the trade as staffless brake, which will be of high power and high 20 efficiency. A further object is to provide a hand brake of the last above character permitting a quick take up of the slack in the brake rigging, as well as a quick release. A further object is to provide a hand brake of 25 the last mentioned character adapted to hold the brakes in applied position without the use of pawls and ratchet heretofore deemed necessary.

Other objects will be in part obvious from 30 the annexed drawings and in part indicated in connection therewith by the following analysis of this invention.

This invention accordingly consists in the features of construction, combination of 35 parts and in the unique relations of the members and in the relative proportioning and disposition thereof, all as more completely outlined herein.

To enable others skilled in the art so fully 40 to comprehend the underlying features thereof that they may embody the same by the numerous modifications in structure and relation contemplated by this invention, drawings depicting a preferred form have 45 been annexed as a part of this disclosure, and in such drawings like characters of reference denote corresponding parts throughout all the views, in which

Figure 1 is an end view of a part of a 50 freight car showing the application of the brake thereto;

Fig. 2 is a side elevation partly in section showing the brake mechanism;

Fig. 3 is a transverse sectional view of the 55 mechanism shown in Fig. 2.

Referring now to the drawings in detail and more particularly to Fig. 1, 5 denotes the end of a freight car of usual construction provided with a platform 6 upon which an operator may stand while applying the 60 brakes. Attached to the end wall in any desired manner is a rectangular casing 7 having an upwardly projecting operating shaft 8 carrying hand operating means such as a wheel 10 adapted to be actuated in applying 65 the brakes. Extending downwardly from the casing 7 is preferably a block chain 11 which passes through the platform 6 and is connected with suitable power transmitting mechanism such as pull rod 12 although a 70 wire cable and drum could obviously be used. To the lower end of this pull rod is connected an ordinary chain 13 passing through a sheave 14 thence rearwardly to the foundation brake rigging beneath the central part of the car. The power is transmitted from this brake rigging to the truck 75 brake mechanism in any desired manner.

The interior of the casing contains certain mechanism now about to be described in detail, so constructed, positioned and arranged that when the hand wheel 10 is rotated power 80 will be transmitted through the mechanism above described to apply the brakes.

This mechanism is shown more clearly in 85 Figs. 2 and 3, and the casing 7 is provided with a plurality of attaching lugs 15 whereby the same may be conveniently secured to the car body. A removable cover 16 is secured to the casing by means of bolts or 90 screws engaging holes 17 in the corners of the casing for permitting convenient access to the interior. Centrally disposed within the casing is an operated shaft 19 carrying a block pulley 18 and a worm gear 20 which 95 for convenience are integrally formed, as clearly shown in Fig. 3. This shaft may be rotated by means of a crank or hand wheel 21 on the front face of the casing when a quick take up is desired. The shaft 8, Fig. 100 2, is provided with a worm 22 adapted to coact with the worm gear 20. The lower end of this shaft 8 is mounted in a bearing member 23 trunnioned in the front and back walls of the casing as shown in Fig. 3 for 105 allowing quick lateral movement.

The shaft 8 is normally held in upright vertical position by means of a lock lever mechanism 24 pivoted at 25 to one of the side walls of the casing. This member 24 110

has a U-shaped portion at one end adapted to embrace the shaft 8. It will be noted that the casing is slotted at 26, whereby as the lock lever 24 is raised the shaft 8 will pivot relatively toward the left about its trunnioned bearing 23, thereby carrying the worm 22 quickly out of mesh with the worm gear 20. This is for the purpose of permitting a quick release of the braking power or quick take up when using the wheel 21. It will be noted that the chain 11 may be of the endless type but is preferably connected in the manner shown in Fig. 2, that is, it passes upwardly over the block pulley 18 and downwardly on the other side through an opening 27 and has a stirrup or enlarged ring 28 to prevent disconnection and also allow the brakeman to place his foot therein whereupon a downward pressure will instantly take up all the slack. One object of this arrangement is to provide a downward pull upon the block pulley and worm mechanism rather than an upward pull, as would be the case if the chain were inserted through the opening 27 and hung down at the opposite side.

This brake mechanism may be operated in substantially the following manner:

The block lever 24 is raised to throw the worm and gear out of mesh and the hand wheel 21 rotated to take up the slack in the brake rigging if the ring 28 is not used. As herein shown one turn of the hand wheel 21 will take up approximately from twelve to fourteen inches of chain which is above the usual amount of slack allowed in the brake rigging. This, however, is not absolutely necessary for even by rotating the hand brake wheel 10 twice about seven inches of chain will be taken up under high power or approximately at a ratio of one to forty. However, assuming that the slack has been taken up by the quick take up means, the lock lever 24 is then swung downwardly which carries the worm 22 into engagement with the worm wheel and then by rotating the brake wheel 10, the brakes may be applied with high power and the parts will hold in the position to which they are turned without the necessity of operating any pawls or ratchets, as usually required. When a release of the brakes is desired, the hand brake 10 may be rotated in the opposite direction or if a quick release is preferred a raising of the lock lever 24 will cause the worm 22 to move out of engagement with the worm pulley 20 thereby allowing the brakes to release under the action of the brake springs associated therewith.

It is thus seen that this invention provides a relatively simple brake mechanism having few parts which are cheap to manufacture and install and not likely to get out of order. The mechanism permits a quick

take up and high power application, as well as a quick release and is therefore highly efficient in operation.

I realize that considerable variation is possible in the details of construction and arrangement of parts without departing from the spirit of my invention, and I therefore do not intend to limit myself to the specific form shown and described. 70

Having thus described my invention what 75 I claim as new and desire to secure by Letters Patent is:

1. In a brake mechanism for railway cars, in combination, a casing adapted to be secured to the end wall of the car having a 80 slot along one side and a removable wall to permit access to the interior thereof, an operating shaft pivoted at one end within the casing and projecting through the slot having a lateral movement therein, a worm 85 on said shaft, a worm gear with which said worm normally meshes, a drum connected with said worm gear, a chain passing about said drum, quick take up means connected with one end of said chain and brake mechanism connected with the other, and means normally holding said worm and gear in mesh but permitting an unmeshing thereof whereby the brakes may be quickly released or the slack taken up by operation of said 90 take up means.

2. In a brake mechanism of the character described, in combination, an operating shaft and operated shaft, worm and gear connections therebetween, means for rotating the operating shaft, means for transmitting the power from the operated shaft, means permitting instant unmeshing of the worm and gear whereby a quick release of the brakes may take place and means connected with the operated shaft whereby it may be manually operated to quickly take up the excess slack in the brake rigging. 100

3. In a brake mechanism of the character described, in combination, an operating 110 shaft having a worm, an operated shaft having a worm gear in mesh with the worm, a block pulley connected with the worm gear, and a chain meshing with said block pulley having quick take up means coacting 115 with the block pulley and adapted to be connected with the brake rigging.

4. In a brake mechanism of the character described, in combination, an operating shaft having a pivotal support, a worm 120 thereon, a gear in mesh with said worm, an operated shaft upon which said worm gear is mounted, a block pulley connected with the worm gear, a chain meshing with said block pulley having one end connected 125 with the brake mechanism and its opposite end provided with a quick take up mechanism, and means engaging the operating shaft adapted to hold the worm and gear normally in mesh but permitting a quick 130

unmeshing thereof whereby the brakes may be released or the slack quickly taken up.

5. In a brake mechanism of the character described, in combination, a casing having 5 a slot in one wall thereof, an operating shaft projecting through said slot and having a pivoted bearing near its lower end whereby it may oscillate back and forth in said slot, a worm on said shaft, a worm gear normally 10 in mesh therewith, means including a member coacting with the casing and operating shaft adapted to hold the shaft against lateral movement, a block pulley operatively connected with the worm gear and a chain 15 coacting with the block pulley adapted to be connected with the brake rigging, and means whereby the block pulley may be turned to quickly take up the slack when said worm and gear are thrown out of 20 mesh.

6. In a brake mechanism of the character described, in combination, an operating shaft and operated shaft, worm and gear connections therebetween, means for rotating 25 the operating shaft, means for transmitting the power from the operated shaft, including a pulley, a chain passing freely over said pulley and a stirrup at the end of said chain whereby a quick take up of 30 the slack may be obtained, and means associated with the operated shaft whereby the same may be turned independently of the operating shaft.

7. In a brake mechanism of the character

described, in combination, a casing having 35 an operating shaft with hand turning means associated therewith, an operated shaft at right angles thereto, power multiplying gearing connecting said shafts, a block pulley on said second shaft, a chain coacting 40 therewith and adapted to be connected with the brake mechanism at one end and having its other end free whereby the slack may be quickly taken up by pulling on said free end, and means permitting the meshing 45 or unmeshing of the geared connections of said shafts at will.

8. In a brake mechanism of the character described, in combination, a casing, a shaft trunnioned in said casing, hand turning 50 mechanism connected therewith outside of said casing, an operated shaft mounted in the casing, worm and gear mechanism connecting said shafts, a pulley on said second shaft, power transmitting mechanism connecting 55 said pulley with the brake mechanism and means adapted to permit or prevent a lateral movement of said operating shaft about its trunnioned bearings to carry said gears into or out of mesh, said power 60 transmitting mechanism including a block chain passing over said pulley and connected with the brake rigging whereby an equal downward pull is exerted on the parts of said mechanism within said casing when 65 the brakes are under tension.

In testimony whereof I affix my signature.
WILLIAM H. SAUVAGE.
